PERCUSSION TOOL

Kenneth L. Berninger, Dayton, Ohio, assignor of
one-half to Wilbur F. Stover, Pleasant Hill,
Ohio

Application October 11, 1949, Serial No. 120,665

5 Claims. (Cl. 81—52.3)

1

This invention relates to a marking tool of the character of a prick punch or center punch that is used to mark a particular spot on the surface of metal or other hard substance by means and mechanism contributing to its construction. In tools of that character it is difficult to place the point of the tool exactly on the spot to be marked, and hold the tool exactly on the spot without slipping while the tool is struck with a hammer. Because of the relatively slippery surface of the hard material to be marked reaction forces in raising the hammer cause the holding hand to slide the tool ever so little so that the hammer hits the tool when it is not on the exact spot intended to be marked. An error therefore occurs, and is likely to be unobserved. To guard against such faults, and to provide a marking tool embodying its own hammer mechanism that will effectively and accurately mark hard material, I make use of a hollow handle for slidably supporting one end of a tool head, a rod-like hammer and a helical spring joined to the tool head and hammer under tension, with an actuating knob at the end of the housing for additionally stressing the spring when it is desired to apply a hammer blow to the tool. The assembled length of the tool, hammer and knob is such, that it exceeds in length between a shoulder on the tool head and the opposing end of the knob, the overall length of the housing, so that when the hammer and tool are engaged, then there is a looseness of the assembled tool head and hammer that permits a slight axial relative movement of the assembly within the housing, the reason for which will presently appear. The housing or handle is intentionally of straight bore tubing with both ends open with the same bore as the main bore of the tube to simplify the act and method of assembly, since the tool head may then be inserted in either end of the tubular housing. The relation of the tubular housing, the spring connecting the tool head with the hammer rod, and the hammer are so proportioned in diameters that the spring acts as a cylindrical spacer and guide for the movement of the hammer when striking the tool head. The reason for that will also appear as the description proceeds.

Further objects and advantages of the present invention will be apparent from the following description, reference being made to the drawings, wherein preferred embodiments of the present invention are clearly shown.

In the drawings:

Fig. 1 is an elevational view of my improved

marking tool, with the hammer partly withdrawn.

Fig. 2 is a longitudinal sectional view substantially as indicated by the line and arrows 2—2 of Fig. 1, but with the hammer fully housed as it normally is in the rest position.

Fig. 3 is an enlarged view similar to Fig. 2, the better to illustrate some of the finer details.

Fig. 4 is a fragmentary enlarged view of the juncture of tool head and handle applied to the work at the instant of marking the work.

Fig. 5 is an enlarged fragmentary sectional view of the relation of parts insuring smoothness of operation and prompt delivery of power.

15 With particular reference to the drawings, 10 refers to a straight bore tubular housing or handle, and which encloses a hammer assembly 12 made up of a tool head 14 and, a hammer rod 16, yieldably retained in engagement at 18 by a closely wound spiral spring 20, which is attached at one end 21 to the tool head 14 and at the other end to the hammer rod 16, at 23, the spring 20 being under such tension that the tool head 14 and the hammer rod 16 are firmly engaged at 18. That is made possible by bonding or otherwise securing one end of the spring 20 to a reduced stem or anvil 22 of the tool head 14. The hammer rod 16 is then passed within the end of the spring until the rod engages the end of the anvil at 18. With the parts in that relation the spring is stretched somewhat until it approaches the top end of the rod where it is similarly attached as indicated at 23. The spring 20 is thereby stretched throughout its length 25 surrounding the rod 16 between the attachments 21 and 23, and constitutes what I choose to call a hammer assembly 12. The hammer assembly is then assembled in the tubular housing 10 by passing the top end where the spring is secured 30 to the hammer rod at 23 into the bottom end of the housing, and moving along until it extends out of the other end, and until a cylindrical portion 24 of the tool head slides within one end of the tubular housing and a square shoulder 26 35 abuts the end of the tube as indicated at 28. The assembled length of the hammer assembly is such that the top end projects beyond the top end of the housing tube. The outside diameter of the cylindrical portion 24 is smaller by a few 40 thousandths of an inch than the inside diameter of the housing 10 that the tool head is capable of easily sliding in and out of the tubular housing. While maintaining the tool head seated against the end of the housing I place about the 45 top end an appropriate cavity filled, with a suit-

able plastic to form a knob 30. The attachments 21 and 23 may be accomplished by any one of several devices but I prefer a method that leaves a few of the extreme end turns of the spring somewhat spaced axially, especially for the attachment 23 where the spaced turns of the spring end after they are bonded or secured to the remote end of the hammer rod, provide anchorage for the moulding of the knob 30 as shown more clearly in Fig. 3. The cavity members are so fashioned that there is a squared end 32 of the knob adjacent the top end of the housing 10 and spaced therefrom somewhat as indicated at 34 in Fig. 3. Alternatively I may cut the end of the knob to that facing and spacing after the moulding operation is completed. When the knob is completed the overall length between the shoulder 26 and the near end of the knob at 32 is greater by the amount of spacing 34 than the extreme length of the housing or handle 10. By reason of that, the hammer assembly 12 with the knob 30 attached can slide easily along the axis of the tubular housing 10 by the amount of the spacing 34 and yet keep the hammer and anvil engagement at 18. Also rotation of the knob 30 will effect easy rotation of the hammer assembly within the housing 10. The only resistance to turning of the hammer assembly within the housing is the journalled relation of the end of the housing and the cylindrical portion 24 of the tool head. The inside and outside diameters of the coiled spring 20 are such that the spring 20 easily slides within the bore of the housing, and along the outside of the hammer rod 16. The inside diameter of the wound spring is sufficiently greater than the cross section of the rod 16 that stretching the spring to the full capacity of the associated elements and parts will not reduce the wound diameter enough to cause binding on the hammer rod 16. Further, the section of the wire from which the spring is wound is such that the annular space 36 surrounding the rod and within the casing is substantially filled by the turns of the wound spring. The preferred relation of the housing 10, the rod 16 and the spring 20 is better shown in Fig. 5 which is an enlarged detail, in section. The spring 20 in preference is a spring wherein the turns are closely spaced when the spring is allowed to shorten to such length that the end of the hammer rod is engaged with the anvil. In Fig. 5 the spacing between turns is shown at 38 to be less than the diameter of the spring wire, while the spacing between the rod 16 and tube 10 is slightly greater than the diameter of the spring wire. By that construction the end of the rod 16 sliding within the spring is substantially like sliding within a continuous tube, and there is so little lateral movement between any two more of the elements 16, 20 and 10 that the rod 16 cannot sway enough to catch and hang up on the inside of one of the turns of the spring, even when the spring is stretched out beyond the end of the housing 10. That type of spring also makes it possible to obtain a relatively large amount of spring force by using a relatively short length of wound spring, since the spring may be stretched a considerable length without approaching the elastic limit of the spring.

In the use of the tool, the point 40 of the tool head whether it be a center punch, chisel point, or nail set, is placed against the work and held with one hand on the exact spot where the stroke is to be delivered. The outside of the

tubular housing 10 may be knurled at 41 or near one end 42 to assist a firm finger grip on the tool. While the point of the tool is held in place against the work with one hand the other hand grasps the knob 30 and pulled away from the top of the housing to stretch the spring and withdraw the hammer rod from engagement with the anvil. The hammer rod is withdrawn a slight amount for a light blow and a greater amount for a heavier blow, all the time pressing downward with the lower end of the housing and tool head against the work. By releasing the knob 30 the spring quickly snaps the hammer rod 16 downward against the anvil 22 and drives the tool head against the work. Fig. 4 shows the relation of the parts as the hammer stroke takes place. The work is indicated at 50, as being a sheet of metal to be marked with a center punch, and the point 40 of the tool head is piercing the surface of the work at 52 somewhat the equivalent of the spacing 54 between the end of the housing and the shoulder 26 of the tool head. The hammer rod 16 and the anvil 22 are about to be separated at the meeting point 18 incident to the inertia of the tool head 14 being actuated by a fully stretched spring. That feature is made possible because of the intended loose fit of the cylindrical portion 24 of the tool head within the end of the housing. All of the stored energy of the stressed spring 16 is expended in driving the tool head, while the housing held in the hand remains substantially stationary, not being driven by the hammer assembly. If the tool head is driven far enough beyond the end of the housing that the cylindrical portion slides entirely out of the end of the housing, which is possible under certain conditions with the release of a fully stressed spring, the outside of the lower end of the spring sliding within the lower end of the housing will guide the return of the tool head to its normal position within the end of the housing after the stroke has been expended.

Although a specific embodiment of the invention has been shown for the purposes of illustration, it will be evident that the invention is capable of various modifications and adaptations within the scope and spirit of the appended claims.

I claim:

1. A percussion tool comprising in combination, a tubular housing of uniform bore open at both ends, a tool head having a cylindrical shank slidably engaged in one end of the housing and a shoulder engageable with the end of the housing, a hammer rod engageable with the tool head and extending beyond the other end of the housing a closely wound helical spring extending the length of the housing and substantially filling the annular space between the inside of the housing and the outside of the hammer rod, means anchoring one end of the spring to the tool head, the end turns of the other end of the spring being separated and tightly engageable about the extending end of the hammer rod, said spring being stressed slightly while the hammer rod engages the tool head, and means anchoring the separated turns of the spring to the extending end of the hammer rod while the spring is slightly stressed, thereby normally keeping the hammer rod in engagement with the tool head, and means including the extending end of the hammer rod for stressing the spring to store up energy for driving the tool head, releasing of

the stressed spring permitting the hammer rod to strike the tool head and drive it axially relative to the housing.

2. A percussion tool comprising in combination, a tubular housing, a hammer assembly enclosed within the housing and including a tool head, a hammer rod engaging the tool head, and a helical spring secured at one end to the tool head and encompassing the hammer rod, means securing the other end of the spring to the remote end of the hammer rod, said spring when secured to the tool head and hammer rod being under light tension for normally engaging the hammer rod with the tool head, said tool head having a reduced portion with a shoulder movably supported in and against one end of the housing, said hammer assembly having the hammer rod and encompassing spring slidably associated with the inside of the housing and the remote end thereof extending beyond the end of the housing when the shoulder of the tool head is against the other end of the housing, and a knob secured to the remote end of the hammer assembly for stressing the spring while holding the tool head against the work, whereby release of the stressed spring permits the hammer rod to strike the tool head and drive the tool head out of the housing somewhat without expending energy to drive the housing.

3. The combination set forth in claim 2 wherein the means securing the said other end of the spring to the remote end of the hammer rod includes spaced end turns of the spring being bonded to the end of the rod and providing anchorage for the knob moulded thereon.

4. The combination set forth in claim 2 wherein the assembled length of the hammer assembly is such that the distance between the shoulder of the tool head and the near end of the knob exceeds the overall length of the housing so that striking of the hammer rod upon the tool head drives the tool head against the work without effecting movement of the housing.

5. A variable stroke percussion tool comprising in combination, an operating assembly includ-

ing a tool head having a shouldered cylindrical portion and an axially extending anvil, a hammer rod aligned with the anvil, a helical spring loosely encompassing the hammer rod and having its ends deformed to firmly engage about the anvil and the end of the rod remote from the anvil, means securing the ends of the spring to the anvil and to the remote end of the rod so that the spring will be slightly tensioned when the end of the hammer rod is engaging the anvil, a tubular housing of uniform bore within which the said operating assembly may be inserted until the shoulder of the cylindrical portion of the tool head engages the end of the housing and the cylindrical portion slidably engages the bore of the housing, and a knob secured to the end of the hammer rod about the secured end of the spring, said knob having an annular shoulder spaced from the adjacent end of the housing when the tool head shoulder engages the first mentioned end of the housing, said tubular housing loosely encompassing the spring and extending throughout the active portion thereof to guide the spring and hammer rod when there is relative movement thereof with respect to the housing, whereby the hammer rod is always aligned with the anvil during a percussion stroke.
